[57] CLAIM

The ornamental design for a container cover, as shown.

DESCRIPTION

FIG. 1 is a front perspective view of the container cover showing my new design;

FIG. 2 is a front elevational view thereof;

FIG. 3 is a top plan view thereof;

FIG. 4 is a rear elevational view thereof;

FIG. 5 is a right side elevational view thereof;

FIG. 6 is a left side elevational view thereof;

FIG. 7 is a bottom plan view thereof; and,

FIG. 8 is a perspective view of a second embodiment of the container cover design having the same design features as shown in FIGS. 1-7 and in which the body is elongated compared to FIG. 1.

The broken line showing of environment in FIGS. 1-8 is for illustrative purposes only and forms no part of the claimed design.
